Attorney:

UNITED STATES PATENT OFFICE

JOHN P. DAVIS, OF ST. LOUIS, MISSOURI, ASSIGNOR TO THE KENNEDYE CORPORATION,
OF ST. LOUIS, MISSOURI, A CORPORATION OF DELAWARE

ROTARY WELL-DRILLING TOOL

Application filed May 28, 1928, Serial No. 281,079. Renewed February 21, 1930.

This invention relates more particularly to improvements in rotary well drilling tools equipped with bit controls in which the drill pipe from the rotary table to the drill bit 5 is divided into two portions, the upper portion delivering rotary power only, while the lower portion transmits not only rotary movement but also pressure against the drill bit within the limits of the control.

10 It has been proposed, in the use of conventional rotary well drilling equipment, to utilize an attachment or device known as a rotary bit control which functions to practically eliminate from the drill pipe all lateral deflection and in addition to permit only a known portion and weight of the drill pipe to rest upon the bit during actual drilling. This rotary bit control in one embodiment comprises a hollow shaft disposed for independent movement in the casing associated with means carried by the casing for rotating the shaft as a unit with the casing, said hollow shaft being connected with weighted means of known predetermined weight, 25 which weight is interposed between the hollow shaft and the drill bit.

The improvement of the present invention more particularly comprises a means for practically closing off the water forced 30 through the drill pipe by the mud pump at the surface of the ground.

Among the objects of the present invention are to provide a means for practically closing off the water forced through the drill pipe by the mud pump; to utilize the downward movement of the rotary bit control in closing off the water and the upward movement for opening a valve and furnishing a 35 free passageway for the water.

40 In practical operation it is proposed to overload the pump and cause it to knock or thud, when the rotary bit control reaches its extreme downward position by practically shutting off the water passing through the 45 drill pipe so that the driller's attention will be called to the fact that the rotary bit control has reached its downward position and must be raised for another drill run before the drill bit will continue to cut the formation.

As a feature, the improvement of the present invention is applicable to conventional rotary well drilling equipment without substantial change in structure or function.

Other objects, features and advantages of the present invention will be more apparent from the following description:

Fig. 1 is an enlarged vertical section of the complete water control valve for a rotary well drilling bit control.

Fig. 2 is a vertical section of the water control valve and the rotary well drilling bit control illustrating the assembly of the two ready for operation.

Fig. 3 is a sectional view taken on line 3—3 of Fig. 2.

Fig. 4 is a transverse sectional view taken on line 4—4 of Fig. 1.

Referring more in detail to the drawings, the water control valve of the present invention adapted for use with a rotary well drilling bit control comprises a casting 1 (which may also serve as a coupling for adjacent sections of drill pipe) provided with a conical valve seat 2 and a guide 3 supported by the ribs 4. Between the ribs 4 are the 70 openings 5.

In the guide 3 moves the pipe or valve stem 7, at the lower end of which is attached a casting 8 provided with openings 9, which 80 casting 8 is adapted to be suitably connected with the upper portion of the rotary well drilling bit control 20. Surrounding the valve stem 7 and secured in fixed relation thereto in any practical manner is a shoulder 10 which functions to limit the downward movement of the movable conical lift valve 11 (as illustrated in Fig. 2) when the latter is not resting on its valve seat 2.

Surrounding the stem 7 and movable thereon is the washer 12, which functions to retain one end of the compression spring 13 which surrounds pipe 7, the other end of said spring being retained by the jam nut 14. Surrounding the upper end of the pipe 7 and screwed thereon is the centering bridge guide 15 adapted to move within the drill pipe 16. Against the bridge 15 is secured the jam nut 17. The end of the pipe 7 may be provided 90

with a cap 18 which in turn may be provided with a small hole 19.

The assembly of the water control valve and the rotary well drilling bit control is shown in Fig. 2, and its operation is as follows:

When the tubular control shaft 20 moves downwardly in the drill pipe 16 it carries the pipe 7 and, of course, the valve 11 with it. 10 When shoulder 21 on tubular shaft 20 closely approaches the shoulder 22, the lift valve 11 seats on the valve seat 2, because the distance between the shoulders 21 and 22 is slightly more than the distance from the shoulder 15 10 on the pipe 7 to the valve seat 2 in the casting 1. As the tubular control shaft 20 continues to move downwardly until shoulder 21 contacts shoulder 22, the spring 13 compresses and holds the valve 11 firmly on 20 its seat 2. When the valve 11 is seated it will be noted that there is no large opening whereby the water may pass through the drill pipe into the tubular control shaft 20. By shutting off the water in this manner, the pump 25 at the surface of the ground which is forcing water in the drill pipe 16 will start to pound and the drilling operator will be notified that the rotary well drilling bit control has reached its extreme downward position 30 and must be raised to the position shown in Fig. 2 before drilling may proceed.

A hole 19, as heretofore described, may be provided in the cap 18, if desired, so that a small amount of water may flow through 35 the drill pipe and out of the drill bit to maintain a circulation of water when the valve 11 is seated or closed. The passage of the small amount of water down the drill pipe and out the drill hole and outside of 40 the drill pipe retards the settlement around the drill bit of all cuttings and particles carried by the water. As is well known, the mud pump forces water down the drill pipe during drilling and this water passes through 45 a hole or holes provided in the drill bit and the water then passes up between the walls of the hole and the outside of the drill pipe and flows out at the surface of the ground. This water carries all the mud, slush, cuttings, et cetera made by the drilling.

It may be well to briefly describe the operation of the rotary well drilling bit control. The sections 16 of the casing are secured together by a special coupling 23. The 55 combination coupling and drive bushing 23 may be provided interiorly with one or more ribs 24 adapted to register with one or more complementary grooves 25 provided in the tubular control shaft 20 within the limits of the rings forming shoulders 21 and 22. The rotary control shaft 20 is illustrated in two sections. To the lower end of the lower section may be secured common drill pipe (not shown) by a conventional pipe coupling (not 60 shown), and to the end of the common drill

pipe may be secured the usual conventional drill bit holder and drill bit (not shown), the drill pipe below the lower section of the rotary control shaft 20 being weighted in a suitable manner so as to dispose a known and predetermined weight on the drill bit, the casing 16 above the rotary control shaft 20 being suspended from the rotary table. For general use the most efficient weight on the drill bit has been ascertained to be approximately 10,000 pounds. 70 75

In the installation and operation of the rotary well drilling bit control, the upper end of the pipe 16 is attached by the conventional pipe coupling to the drill pipe leading through the rotary drill table and connected with the control hoist, while the lower end of the lower section of the rotary control shaft 20 is connected to a drill pipe of the weight desired to rest on the drill bit during 80 85 actual drilling.

With the control hoist, the rotary bit control is lowered into position for drilling and the drill bit is let down until it rests upon the formation to be cut and until the drill control shaft 20 is in its upper position, as 90 illustrated in Fig. 2. The rotary table is then started and as it revolves so will the drill pipe, control device and the drill bit, the rotation imparted to the drill pipe by the rotary table in turn being imparted to the hollow shaft 20 through the medium of the ribs 24 and complementary grooves 25. In addition, since the weight of the pipe below 95 the control shaft 20 rests upon the drill bit, the latter will start cutting and proceed downwardly. Through its own weight the control shaft will also move downwardly. When the control shaft 20 has moved downwardly to a point where the shoulder 21 rests upon the shoulder 22, the drill bit will proceed no further and since the bit is not drilling it will spin. At this time the valve 11 has been carried downwardly with the control shaft 20 and, as illustrated in Fig. 1, practically shuts off the water being forced through the mud pump. The driller then lowers the drill pipe carried by the rotary table a sufficient distance to again space the shoulders 21 and 22 a desired distance apart, after which 105 the drilling may proceed as heretofore described. 110 115

The rotary well drilling bit control is adapted to be placed at any depth below the surface of the ground as a part of the drill pipe transmitting rotary movement and power to drive the drill bit and attached and so arranged in combination with the drill pipe leading to the rotary table at the surface of the ground that the drill pipe carrying within it the rotary well drilling bit control mechanism, and the drill pipe connected thereto and carrying a drill bit will move upward or downward within the limits of the drill bit control without any upward or 120 125 130

downward movement to the drill pipe leading to the rotary table and attached to the hoist at the surface of the ground.

I claim as my invention:

5. 1. A rotary well drilling tool comprising in combination, an outer casing adapted to be rotatably driven, a movable hollow shaft slideable in said casing and extending from the lower end thereof, means carried by said casing for rotating said shaft as a unit with the casing, a valve seat carried by the outer casing and a vertically slideable valve movable for a limited distance with said hollow shaft adapted, when the hollow shaft has moved downwardly a predetermined distance, to seat and substantially close off the supply of water being forced through the hollow shaft.

2. A rotary well drilling tool comprising in combination, an outer casing adapted to be rotatably driven, a movable hollow shaft in said casing, means carried by said casing for rotating said shaft as a unit with the casing, a valve seat carried by the outer casing and a spring tensioned valve cooperatively associated and movable for a limited distance with said hollow shaft adapted, when the hollow shaft has moved downwardly a predetermined distance, to seat and substantially close off the supply of water being forced through the hollow shaft.

3. A rotary well drilling tool comprising in combination, an outer casing adapted to be rotatably driven, a movable hollow shaft in said casing on the end of which a drill bit is to be carried, means carried by said casing for rotating said shaft as a unit with the casing, a valve stem cooperatively associated and movable with said hollow shaft, a valve loosely mounted on said valve stem, a valve seat carried by the outer casing, and upon which the valve is adapted to operate and a shoulder fixed on said stem adapted to limit the pressure which the valve exerts upon the valve seat.

4. A rotary well drilling tool comprising in combination, an outer casing adapted to be rotatably driven, a movable hollow shaft in said casing, means carried by said casing for rotating said shaft as a unit with the casing, a valve stem cooperatively associated and movable with said hollow shaft, a valve loosely mounted on said valve stem, a shoulder fixed on said stem adapted to limit the movement of said valve, and a valve seat associated with said outer casing.

5. A rotary well drilling tool comprising in combination, an outer casing adapted to be rotatably driven, a movable hollow shaft in said casing, means carried by said casing for rotating said shaft as a unit with the casing, a valve stem cooperatively associated and movable with said hollow shaft, a valve loosely mounted on said valve stem, a shoulder fixed on said stem adapted to limit the move-

ment of said valve, a valve seat associated with said outer casing, and a tension spring associated with said stem and interposed between the valve and an end of said stem, said spring in expanded position holding said valve against said shoulder and in compressed position holding said valve against said valve seat.

6. A rotary well drilling tool comprising in combination, an outer casing adapted to be rotatably driven, a movable hollow shaft in said casing, means carried by said casing for rotating said shaft as a unit with the casing, a valve stem cooperatively associated and movable with said hollow shaft, a valve slidably mounted on said valve stem, a valve seat carried by the said casing, and upon which the valve is adapted to operate, a shoulder fixed on said stem adapted to limit the pressure which the valve exerts upon the valve seat, and means for guiding the movement of said valve stem.

7. A rotary well drilling tool comprising in combination, an outer casing adapted to be rotatably driven, a movable hollow shaft in said casing on the end of which a drill bit is to be carried, means carried by said casing for rotating said shaft as a unit with the casing, a valve cooperatively associated and movable for a limited distance with said hollow shaft, a valve seat associated with said outer casing, said valve adapted, when the hollow shaft has moved downwardly a predetermined distance, to substantially close off the supply of water being forced through the hollow shaft.

In testimony whereof I affix my signature.

JOHN P. DAVIS.
